(57) **CLAIM**

The ornamental design for a flatware riser, as shown and described.

DESCRIPTION

FIG. 1 is a perspective view of the flatware riser showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof;

FIG. 7 is a right-side elevation view thereof;

FIG. 8 is a perspective view of an alternative embodiment of the flatware riser of FIG. 1;

FIG. 9 is a front elevation view thereof;

FIG. 10 is a rear elevation view thereof;

FIG. 11 is a top plan view thereof;

FIG. 12 is a bottom plan view thereof;

FIG. 13 is a left-side elevation view thereof; and,

FIG. 14 is a right-side elevation view thereof.

The broken lines in FIGS. 1, 4, 6-8, 11, and 13-14, depicting initials engraved into each side of the flatware riser show unclaimed subject matter.
